UNITED STATES PATENT OFFICE.

ALFRED JOHANN AUSFITTER, OF MUNICH, GERMANY.

DEVICE FOR THE ADJUSTMENT OF THE SIDE ANGLE OF SIGHTING INSTRUMENTS.

Application filed March 25, 1921. Serial No. 455,565.

To all whom it may concern:

Be it known that I, ALFRED JOHANN AUSFITTER, citizen of Austria, residing at Munich, Bavaria, Germany, have invented certain new and useful Improvements in Devices for the Adjustment of the Side Angle of Sighting Instruments; and I do hereby declare the following to be a full, clear, and exact description of the invention, such as will enable others skilled in the art to which it appertains to make and use the same.

My invention relates to a device for the adjustment of the side-angle of sighting instruments, as used in connection with the sighting of pieces of ordnance of any kind, as guns, catapults etc. and as employed in surveying instruments and similar apparatus in which a level forms a portion of the outfit, including an index-finger or pointer, similar to that in a miner's compass, the said finger to be made to remain in any given position independent of any position of the gun or other device on which it is being used.

The object of my invention is to provide for certain improvements in instruments of the class referred to, as will appear from the description hereinafter set forth and made more particularly understood from the drawings herewith in which Figure 1 is a vertical section through a device, as herein described and as particularly employable in connection with sighting and laying a gun-barrel, Figure 2 is a top-view of the instrument, while Figure 3 shows the adjusting device in connection with a level, as used in the aiming of a gun-barrel. Figure 4 is a section on the line A—B of Figure 3. Figure 5 is a top-view upon the anchorage of the device. Figure 6 shows another example of my new construction more particularly referred to and explained hereinbelow, and Figures 7, 8, 9 are detail views of parts of the latter, also hereinbelow more particularly described and referred to.

In the apparatus shown in Figure 1, there is an arm or bar 1 projecting from and mounted on the intermediate carriage of an ordnance and having in its free end a square hole engageable by a square body 2 projecting from a horizontal plate 3 of the instrument. The said plate is in the centre shaped as a bearing 4 in which is loosely rotatable the hub of a horizontal disk 5 secured to the said bearing by a screw 6. The disk

5 shows up the usual lateral graduation marks. A vertical shaft-end or spindle 7 is loosely and turnably passed through the said graduated disk 5, bearing 4 and plate 3. Another horizontal disk 8, carrying the correcting-graduation is keyed unto the axle or spindle 7, close above the disk 5 and there is further provided a loosely rotatable pointer 9, radially extending with its upper end over the disk 8 and adapted to be firmly secured to the same in any position and by any of the known devices, whenever it is to follow the revolution of the axle 7. With the said axle 7 there is connected a flexible shaft 10 which may be flexible throughout or be in the nature of a so-called Cardan-shaft or other jointed shaft, the word "flexible" being used in the specification and claims in a broadly inclusive sense. This shaft 10 has its bottom-end attached to and secured in a horizontal disk 11 rotatably mounted in a cylindric box or case 12. The cover 13 of the box 12 has a curved slot 14 through which there is passed and projects a screw-bolt 15 secured to the disk 11. By drawing-on the nut 16 screwed on the bolt 15 the disk 11 may be adjusted and made fast in any position. The box 12 I prefer to be easily detachable and secured to a cross 17 which may be fastened to the ground by sticking the pointed feet 18 into the same. An earth anchorage is thus formed, this term as used herein being a general one covering any means capable of being fixed to the ground.

As thus appears I provide a graduated member movable with the movable object whose side angle is to be adjusted, an adjustable pointer coacting with said graduated member, an earth anchorage, and flexible connections between said anchorage and pointer, whereby even sudden and considerable movements of the object such as occur on the recoil of a gun, though altering the relative position of the object and the pointer do not change the direction in which the latter points. This enables a gun to be brought back to its aim after firing by mechanical means and without further sighting or calculation.

To the plate 3 there is attached the box 19 to contain a transverse level 20 the position of which may be changed by means of a screw 21 acting in union with a corresponding rack 22 through the medium of a rotatable, but not otherwise movable, hand

operated spindle 23. The level 20 is so connected with the disk 5 that when the level is being adjusted the disk will be turned in one direction or the other. For this purpose there is attached to the body of the level a vertical pivot 24 which engages in a slot 25 of a lever 26, which in turn engages the disk 5.

By the rigid connection of the disk 8 with the flexible shaft 10 thus secured, which flexible shaft may, if deemed proper, be substituted by a so-called Cardan-shaft or any equivalent permitting the revolution of the axle 7 of the pointer 9 independent of the swing of the gun-barrel and being extensible at the same time, any desired position of the pointer 9 turnably connected with the disk 8 may, by correspondingly changing the position of the anchorage, be achieved.

In order to give the gun-barrel any desired position or direction, a rough or preliminary adjustment of the gun barrel may be accomplished by giving its hand-spike a swing and then a precise or final adjustment attained by operating the laying gear until the pointer 9 is at the desired mark in the side graduation of the disk 5.

Thus in aiming or laying the gun the following proceeding may, for instance, be observed:

When the gun has been brought in position the anchorage may by any means be set into the ground. Thereupon the pointer 9 which may be provided with a dioptr, may be loosened and brought in temporary aiming-line by sighting an object as a tree, fence-post or the like which is in the direction of the auxiliary mark or aim, to be determined either by the aid of a chart or by taking the North-South direction as an auxiliary mark-line ascertainable by any ordinary compass. Having now ascertained the angle of the line of auxiliary mark of the gun-barrel and the aim of the gun by means of a goniometer, or on the chart by means of a protractor as used by gunners, it is easy to give to the barrel the exact line or direction to the aim by swinging it until the pointer is at the graduation mark desired.

The missile deviating to the side of the deeper wheel, whenever the wheels of a field-ordnance are in oblique position to each other, this deviation has to be corrected before the ultimate adjustment to the exact sight of the aim. This may be termed correcting for transverse obliquity. For this purpose the transverse level 20 is to be brought to its proper place and, accordingly, the disk 5 more or less turned. In this way the lateral angle is increased or, respectively, reduced by so many degrees or graduation marks as the bullet would deviate owing to the oblique position of the wheel-axle and wheels.

Taking into account this correction the

pointer 9 should, prior to the ultimate precise sighting adjustment on the side-graduation, be placed at the corresponding mark on the graduation for the correction and then made fast on the disk 8. When the pointer 9 has then been set in the proper place on the side-graduation the barrel has been laid or given the exact line with respect to the side and its aiming position duly corrected.

In testing my new device, as herein described, it has been found, however, that in spite of the most careful work the play in the bearings of the joints of the flexible shaft or in the joints of a Cardan-shaft would cause inaccuracies in the operation of the instrument and to avoid this is the object of further improvements, about to be described. These improvements constitute a part of the device and cooperate specially with the rest of the device to the end stated.

While the flexible shaft or Cardan-shaft is for this purpose, as heretofore known, composed of members telescopically movable in each other, one of these members is in my further improved construction so influenced by a spring in the other that in this way the axes of the joints or Cardan-joints are pressed into their bearings and, accordingly, the play in these joints is thus avoided. I, therefore, connect the lower joint rotatably with the bottom-portion of the shaft to be secured in the ground, thus permitting a parallel adjustment of this bottom-portion in its relation to the axle of the pointer 9.

For a better understanding of these improved features I refer to the construction illustrated in Figures 6, 7, 8, 9 hereinabove mentioned which show by way of example the incorporation in this device of a Cardan-shaft of special construction composed of the two portions 10', 10'' of which 10'' is a rod telescopically movable in the tubular socket portion 10' which is by the lower Cardan-joint 27 connected with the bottom-portion 28 of the shaft, the said bottom-portion to be stuck into the ground, while the portion 10'' is by the upper Cardan-joint 27' connected with the axle 7. The said portion or rod 10'' is provided with a longitudinally curved strip 29 guided in a fork 30 attached to the tube 10'. In one of the prongs of the fork 30 there is attached thereto a casing 31 (see Figure 8) in which a spring 32 is inserted which permanently acts against the curved strip 29 and thereby causes a twisting movement of the rod 10'' relative to the tube 10'. The result is that the axes of the Cardan-joint are pressed-on towards their bearings and thus prevent a play in these joints. The lower Cardan-joint 27 is turnable about a bolt or pin 33, the turning being effectuated by worm gear consisting of a

screw-wheel segment 34 secured on the bolt 33 and the worm 35. This permits of a parallel adjustment of the axle 7 relative to the bottom point 28 which adjustment is required to ensure an exact work of the instrument.

I would add that, as already mentioned, the construction and device, as described, is in addition to its use in connection with 10 the aiming of gun-barrels, applicable also in connection with surveying instruments and in taking levels as required in building above ground and below street level. It is adapted to be carried by the movable member, 15 whether permanently a part thereof, or as is ordinarily more convenient, designed for ready removal and replacement.

It is manifest that variations and modifications may be made in the features of 20 construction and arrangement in the adaptation of my device to various conditions without departing from the spirit and scope of my invention and I therefore reserve the right to any modifications as fall within 25 the spirit and scope of my said invention and the terms of the following claims.

What I claim is:

1. A device for side-angle adjustment comprising the combination of a rotatable disk having graduation marks, the said disk being adapted for rigid connection with the object on which it is to be employed, an axle, a pointer thereon coacting with the graduated disk, and a flexible shaft connected with the axle, and means for securing the shaft to the ground, whereby the object may after movement be reset in a predetermined relation to the fixed direction indicated by the pointer by again registering the former mark on the disk with the pointer.

2. In a device for side-angle adjustment the combination with a rotatable graduated disk, a pointer coacting therewith, an earth anchorage and a flexible shaft carrying said pointer and secured to said earth anchorage, of a level, and operative connections between said level and disk including a lever, substantially as described and for the purpose mentioned.

3. In a device for side-angle adjustment the combination with a rotatable graduated disk, and a lever operatively connected therewith, of another disk having a similar graduation and coaxial with the first, an axle on which said second disk is keyed, a pointer loosely turnable on said axle and adjustable on the said second disk, an earth anchorage, and a flexible shaft carrying said pointer and secured to said anchorage, substantially as described and for the purpose mentioned.

4. A device for side-angle adjustment comprising a rotatable disk having a graduation and adapted for rigid connection with

the object on which it is to be employed, an axle, a pointer carried thereby coacting with said disk, a flexible shaft connected with the pointer and securable in the ground, an anchorage and in combination therewith a swingable rotatable disk adjustable in its several positions of revolution, and to which the bottom end of said flexible shaft is concentrically secured, whereby the object may after movement be reset in a predetermined relation to the fixed direction indicated by the pointer by again registering the former mark on the disk with the pointer.

5. A device for side-angle adjustment comprising in combination a pointer, a graduated member with which said pointer coacts and which is adapted for rigid connection with the object on which it is to be employed, an earth anchorage and a flexible shaft comprising two parts telescoping one in the other, one of said parts being connected to said pointer and the other to said anchorage and a spring interposed between said parts and tending to press the axes of the joints against their bearings.

6. A device for side-angle adjustment comprising in combination a pointer, a graduated member with which said pointer coacts and which is adapted for rigid connection with the object on which it is to be employed, an earth anchorage, and a flexible shaft having two parts telescoping one in the other, and one of said parts being connected to said pointer and the other to said anchorage, one of said parts being a tube having a fork and the other a rod received by the said tube and having an offset strip guided in the fork, and a spring supported in one of the prongs of said fork and acting upon said strip.

7. A device for side-angle adjustment comprising in combination a pointer, a graduated member with which said pointer coacts and which is adapted for rigid connection with the object on which it is to be employed, an earth anchorage and a flexible shaft having a rod and a tubular portion, the former telescoping in the latter and one of said parts being connected to said pointer and the other to said anchorage, a bottom-end and a bottom-end joint rotatably connected with the bottom-end of the shaft, substantially as described and for the purpose mentioned.

8. A device for side-angle adjustment comprising in combination a pointer, a graduated member with which said pointer coacts and which is adapted for rigid connection with the object on which it is to be employed, an earth anchorage, and a flexible shaft having a rod and a tubular portion, the former telescoping in the latter and one of said parts being connected

to said pointer and the other to said anchorage, a bottom-end of the shaft, a bottom-end joint rotatably connected with the said bottom-end, and in combination therewith a bolt-and-worm-gear, substantially as described and for the purpose mentioned.

9. A device for side-angle adjustment comprising a graduated member adapted to be carried by the movable object whose side-angle is to be adjusted, an adjustable pointer co-acting with said graduated member, and means for insuring that the pointer once it has been given its final adjustment shall continue to point in the desired direction notwithstanding movements of said object, said means comprising an earth anchorage, and universally flexible connections between said anchorage and pointer.

10. A device for side angle adjustment comprising a graduated member adapted to be carried by the movable object whose side angle is to be adjusted, an adjustable pointer co-acting with said graduated member, a second graduated member movable relatively to the first and coaxial therewith and with said pointer, and means for insuring that the pointer once it has been given its final adjustment shall continue to point in the desired direction notwithstanding movements of said object, said means comprising an earth anchorage, and universally flexible connections between said anchorage and pointer, said second graduated member being also connected thereby with said anchorage.

11. A device for side angle adjustment comprising a graduated member adapted to be carried by the movable object whose side angle is to be adjusted, an adjustable pointer co-acting with said graduated member, means for altering the position of said graduated member to correct for transverse obliquity of the object, and means for insuring that the pointer once it has been given its final adjustment shall continue to point in the desired direction notwithstanding movements of said object, said means comprising an earth anchorage, and universally flexible connections between said anchorage and pointer.

12. A device for side angle adjustment comprising a graduated member adapted to be carried by the movable object whose side angle is to be adjusted, an adjustable pointer co-acting with said graduated member, an adjustable level and operative connections between said level and said graduated member, for altering the position of said graduated member to correct for transverse obliquity of the object, and means for insuring that the pointer once it has been given its final adjustment shall continue to point in the desired direction notwithstanding movements of said object, said means comprising an earth anchorage, and universally flexible

connections between said anchorage and pointer.

13. A device for side angle adjustment separable from the movable object whose side angle is to be adjusted and comprising a graduated member adapted to be rigidly secured to the movable object for movement therewith, an adjustable pointer coacting with said graduated member, and means for insuring that the pointer once it has been given its final adjustment shall continue to point in the desired direction notwithstanding movements of said object, said means comprising an earth anchorage, and universally flexible connections between said anchorage and pointer.

14. A device for side-angle adjustment comprising a graduated member adapted to be carried by the movable object whose side-angle is to be adjusted, an adjustable pointer co-acting with said graduated member, and means for insuring that the pointer once it has been given its final adjustment shall continue to point in the desired direction notwithstanding movements of said object, said means comprising an earth anchorage, and universally flexible connections between said anchorage and pointer comprising spring means for taking up play in said connections.

15. A device for side-angle adjustment comprising a graduated member adapted to be carried by the movable object whose side-angle is to be adjusted, an adjustable pointer co-acting with said graduated member, and means for insuring that the pointer once it has been given its final adjustment shall continue to point in the desired direction notwithstanding movements of said object, said means comprising an earth anchorage and a flexible shaft connecting said anchorage and pointer and having relatively turnable co-axial members and spring means for effecting such turning to take up play.

16. In a device for side angle adjustment, a graduated member adapted to be secured to the movable object with which the device is to be used, an adjustable pointer co-acting with said graduated member, an axle, carrying said pointer and coaxial with said graduated member, and a universally flexible shaft having one end adapted to be anchored in the ground and the other connected to said axle.

17. In a device for side angle adjustment an earth anchorage comprising a base having spurs to grip the ground, a box removably secured to said base, a disk mounted to swing on its axis in said box, means for securing said disk in adjusted positions, and a flexible shaft whose lower end is secured concentrically to said disk.

In testimony whereof I hereunto affix my signature.

ALFRED JOHANN AUSPITZER.
